UNITED STATES PATENT OFFICE.

WILLIAM G. JACKSON, OF PENNGROVE, CALIFORNIA.

HEN'S NEST.

1,182,175.

Specification of Letters Patent.

Patented May 9, 1916.

Application filed August 18, 1915. Serial No. 46,072.

To all whom it may concern:

Be it known that I, WILLIAM G. JACKSON, a citizen of the United States, residing at Penngrove, in the county of Sonoma and State of California, have invented new and useful Improvements in Hens' Nests, of which the following is a specification.

The present invention relates to improvements in nests for domestic fowls, the object of the invention being to provide means in such a nest for preventing the hens from getting on to the nest with muddy feet, to prevent brooding hens from crowding and breaking the eggs, to prevent the hens from eating the eggs, and to prevent the hens from roosting in the nest at night time.

In the accompanying drawing, Figure 1 is a vertical transverse section of my improved nest, open for use; Fig. 2 is a broken front view thereof; Fig. 3 is a view similar to Fig. 1 of the nest in its closed position.

Referring to the drawing, 2 indicates end posts, to which are secured end pieces 3, to which ends are secured a vertical series 25 of transverse bars 4, the mediate portion 5 of each bar having parallel upper and lower sides, but the terminal portions 6 tapering to the ends, as clearly shown in Fig. 1. Upon said mediate portions of said bars are secured longitudinal boards 7, between which boards are secured vertical partitions 8, of much less width than the width of the end pieces 4. To the lower portions of the vertical edges of said partitions are secured 35 narrow longitudinal strips 9, to which are secured narrow horizontal boards 11, to the outer ends of which are hinged, as shown at 12, longitudinally extending lids 13, the outer edges of which lids, when raised, can 40 rest against the vertical edges of the partitions, and when lowered rest upon the tops of longitudinally extending wall sections 14, the ends of which are secured to the end posts. On the downwardly sloping terminal portions 6 of the upper edges of the bars 45 are loosely supported bottom boards 16. On the upper edges of the uppermost partitions are secured longitudinally extending boards 17 forming a cover. From the intermediate 50 wall sections extend outwardly shelves 18 forming landing places to facilitate the entrance of the hens to the intermediate nests. These shelves are hinged at their inner edges, as shown at 20, to the wall sections

14 and are supported by hooks 25, so that 55 they can be dropped when the nests are closed.

I have herein shown a vertical series of three rows of nests, but it is to be understood that this vertical series may contain any 60 number of said rows of nests. In all such cases the intermediate rows of nests will be provided with shelves, the shelves being unnecessary for the lowermost and uppermost rows.

The apparatus is used in the following manner. The hen alights on one of the longitudinally extending lids, or on the shelf leading thereto, and walking inwardly, arrives at the longitudinal board 7 70 and between two partitions 8, which constitutes a nest. After the hen has laid an egg and when she leaves the nest, the egg will disappear at once to one side or the other of the narrow board 7, rolling down a slightly 75 sloping bottom board 16, and will be arrested at the bottom of said board by a wall section 14. In this position it can not be contaminated by muddy feet or other source of defilement. The eggs can easily be collected from the receptacles into which they have rolled by raising the lids 13.

Should it be desired to exclude the hens from the nests, and to prevent roosting thereon at night time, the lids 13 are raised 85 into the position shown in Fig. 2, and the bottom boards 16 are raised and rest against the lids 13, thereby effectually shutting off the hens from the nests. In this position the surfaces of the bottom boards 90 which are normally uppermost will now be undermost and will be protected from dirt, and any matter which may have become deposited upon the said uppermost surfaces will be knocked off and fall to the earth. 95

Nests will of course be made of such length, width and height as may be found most convenient. Since the width of either entrance to the nest is less than the length of the nest the hen would find it difficult to 100 turn around in the nest to sit cross-wise to lay an egg and the egg would consequently have to roll out on the bottom board.

I claim:—

1. The combination of supports, a vertical series of central boards supported by said supports, a vertical series of vertically extending partitions between the boards of

- the series, downwardly and outwardly sloping bottom boards adjacent to said central boards, and movable lids over the space immediately above said bottom boards.
5. The combination of supports, a vertical series of central boards supported by said supports, a vertical series of vertically extending partitions between the boards of the series, removable downwardly and outwardly sloping bottom boards adjacent to said central boards, and movable lids over the space immediately above said bottom boards.
10. The combination of supports, a vertical series of central boards supported by said supports, a vertical series of vertically extending partitions between the boards of the series, removable downwardly and outwardly sloping bottom boards adjacent to said central boards, and hinged lids over the space immediately above said bottom boards.
15. The combination of supports, a vertical series of central boards supported by said supports, a vertical series of vertically extending partitions between the boards of the series, removable downwardly and outwardly sloping bottom boards adjacent to said central boards, and hinged lids over the space immediately above said bottom boards.
20. The combination of supports, a vertical series of central boards supported by said supports, a vertical series of vertically extending partitions between the boards of the series, removable downwardly and outwardly sloping bottom boards adjacent to said central boards, and hinged lids over the space immediately above said bottom boards.
25. The combination of supports, a vertical series of central boards supported by said supports, a vertical series of vertically extending partitions between the boards of the series, removable downwardly and outwardly sloping bottom boards adjacent to said central boards, a vertical series of wall sections at the lower ends of said bottom boards, and outwardly extending shelves supported by the intermediate wall sections, and movable lids over the space immediately above said bottom boards.
30. The combination of supports, a vertical series of central boards supported by said supports, a vertical series of vertically extending partitions between the boards of the series, removable downwardly and outwardly sloping bottom boards adjacent to said central boards, a vertical series of wall sections at the lower ends of said bottom boards, and movable lids over the space immediately above said bottom boards.

boards, and movable lids over the space immediately above said bottom boards.

5. The combination of supports, a vertical series of central boards supported by said supports, a vertical series of vertically extending partitions between the boards of the series, downwardly and outwardly sloping bottom boards adjacent to said central boards, a vertical series of wall sections at the lower ends of said bottom boards, and outwardly extending shelves supported by the intermediate wall sections, and movable lids over the space immediately above said bottom boards.

6. The combination of a series of central boards, a series of vertical partitions all forming with the central boards nests, and outwardly and downwardly sloping bottom boards adjacent to the central boards on each side of the same, the distance between the partitions being sufficiently great to permit a hen of ordinary size to pass, but not to turn, therebetween.

In testimony whereof I have hereunto set my hand in the presence of two subscribing witnesses:

WILLIAM G. JACKSON.
